F. M. SLOUGH,
TELEPHONE SYSTEM,
APPLICATION FILED DEC. 26, 1916.

1,351,799.

Patented Sept. 7, 1920.

UNITED STATES PATENT OFFICE.

FRANK M. SLOUGH, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

TELEPHONE SYSTEM.

1,351,799.

Specification of Letters Patent. Patented Sept. 7, 1920.

Original application filed May 15, 1915, Serial No. 28,251. Divided and this application filed December 26, 1916. Serial No. 138,710.

To all whom it may concern:

Be it known that I, FRANK M. SLOUGH, a citizen of the United States, residing at Rochester, in the county of Monroe and State of New York, have invented certain new and useful Improvements in Telephone Systems; and I do hereby declare the following to be a full, clear, and exact description of the invention, such as will enable others skilled in the art to which it appertains to make and use the same.

My invention relates to telephone systems and has for its object the provision of means for registering the completed connections made by the operator, so as to keep an accurate account of the completed connections she has made. I aim to produce a system which accomplishes these purposes without registering or accounting for the conversations between the operator and a subscriber, such as occur when a subscriber asks for the time, or a subscriber is called to be awakened in the morning, or for some similar purpose.

These and other objects of my invention will be understood from a description of a particular embodiment of the same.

This application is a division of my application Serial No. 28,251, filed May 15, 1915, Patent No. 1,262,112, April 9, 1918.

The drawing shows diagrammatically a particular embodiment of a telephone system involving my invention.

I will first describe in a general way the apparatus shown in the drawing and its operation, and will then give a particular description thereof.

At A is shown a telephone line which will herein be referred to as the calling line. At B is shown a substation on the line, which will be referred to as the calling substation. At C is shown the main or central station of the system, which is equipped with telephone line interconnecting mechanism for the purpose of placing telephone lines in interconnection one with the other, so that the subscribers thereon may converse. The interconnecting means is shown as link conductors and in the particular embodiment illustrated as a cord circuit designated by the reference D. Although I have shown a cord circuit in the embodiment illustrated in

the drawing, it will be understood that any suitable telephone line interconnecting mechanism may be employed. At E is shown a second telephone line which may hereinafter be spoken of as the called line. A number of stations are connected to the line E, one of which is shown at F, and which may hereinafter be referred to as the called substation. It will be understood that any suitable number of stations may be connected to either of the telephone lines.

Means are provided for connecting the link connectors or telephone line interconnecting mechanism with the telephone lines, here illustrated as switching means H and G, which may consist of lugs and jacks. The switching means H, hereinafter referred to as the answering switching means, may consist of a plug P and a jack J and the switching means G, which may hereinafter be referred to as the calling switching means, may consist of a plug P₁ and a jack J₁. The operator's set is shown at K, a ringing key at L, the master key at M and a ringing machine at N. Portions of a second cord circuit are indicated at D₁, provided with switching means H₁ and G₁. The mechanism for registering the completed calls is shown at O and O₁.

When the calling subscriber desires a connection, the central station is signaled through the operation of the usual line relay and line lamp placed before the operators, one of whom responds in the usual way by operating the switching means H or H₁, by inserting the plug of the switching means employed into the jack thereof. If the switching means H is employed, the plug P is inserted into the jack J. The relay R will be operated over a circuit including the relay R—the resistance Z and the cut-off relay R₁. If, however, prior to the closing of the switching device H the switching device H₁ shall have been operated by another operator, who thus "captures the call," the relay R will not operate because most of the current which would otherwise flow through the relay R will be traversing a circuit including the relay R₂ and the shunt 1 of the device Z₁. Assuming, however, that no other cord is connected to the line at A at the time the device H is operated, the relay R

will be energized, making capture of the call and shunting the device Z and making it impossible for a connection to be made through any other cord with the line A, as explained. The relay R will also close the strand 2 of the cord circuit and close contacts in the circuit of the automatic listening relay R₃. The relay R will also open contacts in the circuit connections of the 10 magnet R₄.

When the strand 2 is completed, the relay R₅ will be operated over a circuit including the line A, in a manner well understood, completing the circuit of the automatic listening relay R₃, which will be energized, completing a circuit of the magnet X and causing the operation of the register O by stepping up the wheel o through the pawl p. The details of this register are not illustrated, as register details are well understood and it will be apparent that I may employ any suitable register.

R₃ also connects the operator's set K to the cord, so that the operator can now communicate with the subscriber at B. Learning that it is the subscriber at F that is desired, the line E may be tested in the usual manner, or the operator may plug in without the usual delay due to testing. A circuit will be completed through the magnets R₆ and R₇. If the called line is busy, a special signal will be given to the operator to indicate this fact to her. The operation of the mechanism to give this signal is described in the parent application and is not repeated here.

If the called line is idle and the switching device G operated, the relay R₆ will be operated, breaking the circuit of the relay R₃ and disconnecting the operator from the cord. The operator then operates the ringing key L, at the same time closing the master key M and completing a circuit through the ringing relay R₄, which immediately locks itself independently of the key. The closing of the key M also completes a circuit through the relay Y, which, in the embodiment shown, is in series in the circuit of the relay R₄. The relay Y will be operated, stepping up the wheel o₁ of the portion O₁ of the register through the operation of the pawl p₁ and completing the register of the call. The ringing takes place and when the called subscriber responds, the circuit of the ringing relay is interrupted and the magnet of Y deenergized.

It will be seen that the register or counting device will not be completely operated unless both lines are connected together and the ringing of the subscriber takes place.

A detailed description of the operation is as follows: When the subscriber at B takes the receiver 4 off the hook 5, the latter being spring pressed upward, will close a switch 6 in the line A. This will complete a circuit

through the relay 7, as follows: ground 8, battery 9—relay 7—switch 10—conductor 11—switch 6—conductor 12—switch 13—to ground at 14, causing the actuation of the relay 7, which closes a switch 15 in the circuit of the line lamps 16, 16₁ and 16₂, which will be lighted in multiple over the following circuits:—8—9—15—17—to ground at 18. The lamps will be at various positions at the main station, and one of the operators 75 will answer the call. In this case, we will assume that the operator who has charge of the cord D inserts the plug P into the jack J, thereby connecting the cord to the line. The contacts 19, 20 and 21 of the cord will 80 register respectively with the contacts 22, 23 and 24 of the jack. The following circuit will immediately be completed: ground 14—cut-off relay R₁—conductor 25—contact 24—contact 21—switch device 26—conductor 85 27—resistance Z—relay R—battery 28—to ground 29. The relay R₁ will be energized, disconnecting the line lamp and line relay from the line by opening the switches 10 and 13. The relay R will be energized opening 90 a switch 30 for a purpose to be described, closing a switch 31 in the circuit of the relay R₃ and closing a switch 32, thereby completing a shunt 34 about the resistance device Z, and making the circuit of the relay R independent of said device.

Now, if a second operator were to plug into a jack of the line A, for example, suppose the operator controlling the cord D₁ were to operate the switching device H₁, then 100 the current which flowed through the relay R₂ would not be sufficient to operate the said relay because of the presence of the lower resistance circuit of the relay R including the shunt 34. The relay R also closes a 105 switch 33 in the strand 2, completing that strand. As soon as the switch 33 is closed, a circuit is closed for the relay R₅ as follows: ground 35—upper winding of R₅—conductor 36—2—33—19—22—12—6—11—23—110 20—37—3—38—lower winding of relay R₅—battery W—to ground 39. The relay R₅ opens the switch 40 and closes the switches 41 and 42. A circuit is now completed for the relay R₃, as follows: ground 115 44—switch 31—conductor 45—R₃—conductor 46—switch 42—conductor 47—switch 48—conductor 49—conductor 50—W—39. The relay R₃ closes a switch 51, completing a circuit through the device X as follows: 120 ground 52—X—conductor 53—switch 51—46—42—47—48—49—50—W—39. The device X operates the device O. The relay R₃ also closes the switches 54 and 55, connecting the operator's set K to the strand of the cord 125 circuit and enabling the operator to learn from the subscriber, the subscriber desired. Assuming that the subscriber desired is the subscriber at F, the operator operates the device G by inserting the plug P₁ into the jack 130

J₁. Assuming that the line E is busy; that is, that a cord is already connected thereto, for example, that the cord at D₁ is connected to the line E by the presence of the plug P₂ in the jack J₂,—a circuit will then be completed as follows: 58—59—60—R₆¹—ground 61. Now, if the switching device G is operated, the current flow through the relay R₈ will not be sufficient to cause the actuation 10 of the same, owing to the shunt thereof through the relay R₆¹. The characteristics of the relay R₇, however, are such that it will be operated by the slight flow of current passing through the branch containing the relay R₆, even when the branch containing the relay R₆¹ diverts most of the current therefrom. Relay R₇ being energized, closes a switch 62 shunting the relay R₈, which lets go its armature, closing a switch 63. The 20 operator will then get a special busy tone from the device Q through the conductor 64, and her receiver 65, which will indicate to her that the line is busy, when she will withdraw her plug P₁. Assuming, however, that 25 the line E is idle, the operation of the device G will complete a circuit for the relay R₆, as follows: ground 58—59—69—conductor 70—R₇—conductor 71—switch 72—relay R₆—49—50—W—39. R₆ will be energized, completing an alternate circuit for itself and excluding therefrom the relay R₇. This alternate circuit will be as follows: 58—59—69—70—72—R₆, and as before. Relay R₆ opens the switch 48 in the circuit of the relays X 30 and R₃, completing the operation of the register device O, and causing the disconnection of the operator's set from the cord. A switch 73 is also closed for a purpose to be described.

40 The subscriber at F is now rung by operating one of the ringing keys, say the keys L and M. When the key M is operated, the following circuit is completed: 75—M—78—R₄—79—Y—switch 80—conductor 81—41—45 73—49—50—W and 39. This is the circuit that is completed when the plug P is in the jack J and the calling subscriber is on the line. If, however, the plug P is in the jack J and the calling subscriber is not on the line, this circuit will not be completed, because the circuit of the relay R₅ would have been interrupted at the substation B, and the said relay deenergized, causing an interruption of the circuit of the relay R₄ at 41, 50 which has been described. This is of especial use, because frequently the subscriber at F does not respond, and after waiting a reasonable length of time, the subscriber at B suspects that F will not respond, and retires.

55 Under these circumstances the automatic ringing will be interrupted. An alternate path is provided for this circuit to enable the operator to ring the subscriber F independently of any connection to a calling line, 60 for example, when it is desired to call F in the morning, or call him to communicate with him for some other reason. Assuming, therefore, that the plug P has not been inserted into the jack J, the circuit of the relay R₄ will be as follows: 75—M—78—R₄—79—Y—80—85—switch 30—conductor 86—switch 73—49—50—W—39. When relay R₄ has been energized, a switch 90 is operated, completing a locking circuit for the relay R₄, which is independent of the key M, 75 so that no matter how often the key M is now operated, neither the relays R₄ nor Y will be effected, thus enabling the operator to use the key M for other purposes. The relay R₄ will interrupt the strand 2 by 80 opening a switch 91 therein, and close switches 92 and 93 in the ringing circuit, which will be as follows: ground 93—source of ringing current N—off and on through the commutator 94—L—conductor 95—relay R₉—switch 92—through the switching device G—over the line E—back through the switch 93—resistance device 96—booster 97—50—W to ground 39. A portion of this circuit will pass through a multiple of the 90 device 96, 97 and W as follows: conductor 3—the switching device H—the calling line—the subscriber's set B—to ground at 35 through conductor 36—and the upper coil of the relay R₅. The flow of current through 95 this multiple will indicate to the calling subscriber that the ringing is going on and appease his impatience during the time necessary to secure the attention of the subscriber F. As soon as subscriber F responds, the flow of current through the relay R₉ will be such that this relay will be 100 operated, closing a switch 100 and completing a shunt of the relay R₄, thereby diverting the current from the relay R₄, which 105 will be deenergized, releasing its armatures and restoring the switches controlled thereby to the condition illustrated in the drawing.

When the relay Y was operated, it closed 110 a switch 101 in the circuit of the register device O₁. The response of the calling subscriber and the closing of the switch 91 will complete a circuit through the relay R₁₀ as follows: ground 102—winding 103—conductor 2—91—through the switching device G and over the line E and the substation circuit at F—through the switch 93—conductor 104—winding 105—battery W—ground 115 39. The relay R₁₀ opens the switch 80 in the circuit of the relay Y and causes the completion of the actuation of the register. With the apparatus in this condition, the conversation takes place, and at the termination of the conversation, or as soon as the 120 subscriber B hangs up, the circuit of the relay R₅ will be broken, thereby completing a circuit for the relay R₁₁ as follows: 44—31—R₁₁—110—40—73—49—50—W—39. The relay R₁₁ 125 interrupts the strand 3 at 37, 130

completes a locking circuit for itself by closing a switch 111, and interrupts the circuit of the relay R at 26. The relay R will then release the switches controlled by it, interrupting the strand 2 at 33. The operator may then withdraw the plugs from the jacks and the system will be restored to normal.

I have illustrated this embodiment of my invention and the details shown therein for the purpose of describing the invention, and not that I wish to be limited to this particular form or to the details shown, since it will be apparent to those skilled in the art that many departures may be made from such form and details, without departing from the spirit of the invention.

I claim:—

1. In a telephone system, the combination with a connection register, a calling telephone line, a called telephone line, a link circuit for interconnecting the lines, a calling subscriber's supervisory relay and a called subscriber's supervisory relay, an operator's listening relay under the joint control of the said calling and called subscribers' supervisory relays, means to cause the said calling subscriber's supervisory relay and the said operator's listening relay to automatically operate when connection is made with a calling subscriber's line, under the control of the calling subscriber's substation apparatus, a register circuit for the said register comprising normally open contacts of the said listening relay and of the said calling subscriber's supervisory relay and normally closed contacts of said called subscriber's supervisory relay, and means to cause the actuation of the called subscriber's supervisory relay when connection is made with a line of the called subscriber, by the said link circuit.

2. In a telephone system, the combination with a connection register, a calling telephone line, a called telephone line, a link circuit for interconnecting the lines, a calling subscriber's supervisory relay and a called subscriber's supervisory relay, an operator's listening relay under the joint control of the said calling and called subscribers' supervisory relays, means to cause the said calling subscriber's supervisory relay and the said operator's listening relay to automatically operate when connection is made with a calling subscriber's line, under the control of the calling subscriber's substation apparatus, a register circuit for the said register comprising normally open contacts of the said listening relay and of the said calling subscriber's supervisory relay and normally closed contacts of said called subscriber's supervisory relay, and means to cause the actuation of the called subscriber's supervisory relay when connection is made with a line of the calling subscriber, by the said link circuit, and talking strands

for the said link circuit, the said register circuit comprising neither of the said talking strands.

3. In a telephone system, the combination of a plurality of telephone lines, substation apparatus on the said lines, a link circuit for interconnecting the lines, a register for each link circuit, an operating circuit for each register, a ringing key for the said link circuit adapted when operated to apply a source of ringing current to a called subscriber's line to which the link circuit has been connected, means under the control of the calling substation apparatus to maintain the application of the said ringing current to the called subscriber's line, means under the control of the said ringing key to include a source of current in circuit with the said register, means to maintain the operative condition of the said register, said means being under the control of the said ringing current maintaining source, and disabling means under the control of the called substation to disable the said ringing current maintaining means.

4. In a telephone system, the combination with a connection register, a calling telephone line, a called telephone line, a link circuit for interconnecting the lines, a calling subscriber's supervisory relay and a called subscriber's supervisory relay, an operator's listening relay under the joint control of the said calling and called subscribers' supervisory relays, means to cause the said calling subscriber's supervisory relay and the said operator's listening relay to automatically operate when connection is made with a calling subscriber's line, under the control of the calling subscriber's substation apparatus, a register circuit for the said register comprising normally open contacts of the said listening relay and of the said calling subscriber's supervisory relay and normally closed contacts of said called subscriber's supervisory relay, and means to cause the actuation of the called subscriber's supervisory relay when connection is made with a line of the calling subscriber, by the said link circuit, a second link circuit organized like the first link circuit, a plurality of connection terminals for each calling line, whereby a plurality of link circuits may be simultaneously connected to the said telephone line, and disabling means for the said calling subscriber's supervisory relay and operator's listening relay of a connected link circuit associated with a first connected one of the link circuits and the said calling telephone line.

5. In a telephone system, the combination with a plurality of telephone lines, a link circuit for interconnecting a calling one with a called one of the said lines, a connection register for the said link circuit, a ringing key adapted when operated to continuously

apply a source of intermittent ringing current to the terminals of the called line to which the link circuit has been connected, means to cause the actuation of the said 5 register when the said ringing current has been applied to the called line terminals, means to prevent the actuation of the said register and the said ringing means by the operation of the said key, when connection 10 is made with a terminal of a busy desired line, a source of busy tone current, and means to apply the said source to a talking strand of the said link circuit upon the operation of the said ringing and registering 15 preventing means.

6. In a telephone system, the combination with a plurality of telephone lines, a link circuit for interconnecting a calling one with a called one of the said lines, a connection 20 register for the said link circuit, a ringing key adapted when operated to continuously apply a source of intermittent ringing current to the terminals of the called line to which the link circuit has been connected, means to cause the actuation of the 25 said register when the said ringing current has been applied to the called line terminals, means to prevent the actuation of the said register and the said ringing means by 30 the operation of the said key, when connection is made with a terminal of a busy desired line, an operator's circuit adapted to be connected with talking strands of the 35 said link circuit, a source of tone current adapted to be connected with each of the said talking strands, means to prevent the application of the said ringing tone current, the last-named preventing means being normally operative, and means to disable the 40 said last-named preventing means under the control of the said first-named preventing means.

7. In a telephone system, the combination with a plurality of telephone lines, a plural-

ity of link circuits adapted to interconnect 45 calling with called ones of said lines, a source of ringing current, means in each link circuit to apply the said source to the terminals of a called line with which the link circuit is connected, a second set of terminals 50 for the called line to which a second link circuit may be connected, a relay in each link circuit adapted to be operated when connection is made with a called line, and circuit connections controlled by each of 55 the said relays adapted when the said relay is operated to prevent the actuation of the like relay in a second link circuit which subsequently is connected to the same called telephone line, said ringing current applying 60 means being only operative when the said relay associated with the same link circuit as the said ringing current applying means is operated, and a connection register associated with the said link circuits and adapted 65 to be operated when the said ringing current applying means is operated.

8. In a telephone system, the combination with a plurality of telephone lines, a link circuit for interconnecting a calling one 70 with a called one of the said lines, a connection register for the said link circuit, a ringing key adapted when operated to continuously apply a source of intermittent ringing current to the terminals of the called line to 75 which the link circuit has been connected, means to cause the actuation of the said register when the said ringing current has been applied to the called line terminals, and means to prevent the actuation of the said 80 register and the said ringing means by the operation of the said key, when connection is made with a terminal of a busy desired line.

In witness whereof, I have hereunto set 85 my hand this 16th day of December, 1916.

FRANK M. SLOUGH.
